UNITED STATES PATENT OFFICE

ELLIOTT B. MABEE, OF BROOKLYN, NEW YORK

DESIGN FOR A BASIN FOR MEDICAL AND DENTAL PURPOSES

Application filed September 17, 1929. Serial No. 32,777. Term of patent 14 years.

To all whom it may concern:

Be it known that I, ELLIOTT B. MABEE, a citizen of the United States of America, residing in the borough of Brooklyn, in the county of Kings, city and State of New York, have invented a new, original, and ornamental Design for Basin for Medical and Dental Purposes, of which the following is a specification, reference being had to the accompanying drawing, forming part thereof.

The drawing is a perspective view of a basin showing my new design.

I claim:

The ornamental design for a basin for medical and dental purposes, as shown.

ELLIOTT B. MABEE.
